APPARATUS FOR ORE SEPARATION OR CONCENTRATION

Sven Malke, Milwaukee, and Eric A. Kjellgren, West Allis, Wis., assignors to A. O. Smith Corporation, Milwaukee, Wis., a corporation of New York

Application March 13, 1935, Serial No. 10,756

2 Claims. (Cl. 209—120)

This invention relates to improved apparatus for use in ore concentration or separation and specifically to apparatus of this kind for the treatment of dry ores.

5 In the art of ore separation it has been heretofore proposed to project ore through the air to effect a preliminary classification of the ore and to screen or otherwise treat the material thus classified to separate the valuable material from other material with which it may be mixed.

An object of this invention is to provide an improved apparatus for projecting ores for use in connection with such methods of separation.

15 Other objects of the invention will be clear from the accompanying detailed description and the drawing in which:

Figure 1 is a longitudinal elevation of the apparatus in which parts are shown in section;

20 Fig. 2 is a vertical section taken on the line 2—2 of Figure 1; and

Fig. 3 is an enlarged view of a portion of the accelerator wheel.

Referring to the drawing, the shafts 1 and 2 are supported in bearings 3 and 4 respectively by suitable pedestals 5 and carry the pulleys 6 and 7 respectively. The pulley 6 is rotated in the direction indicated by the arrow by an electric motor or some other suitable driving means not shown in the drawing. A continuous belt 8 passes around the pulleys 6 and 7 and under an accelerator wheel 9. The accelerator wheel 9 is mounted on shaft 11 which rotates in bearings 12 and 13 supported on suitable pedestals 14. The accelerator wheel may conveniently be an idler wheel which is driven by the friction of the belt as shown in the drawing. The accelerator wheel 9 may be composed of a front plate 15 and back plate 16 flanged outwardly at 17 to provide for attachment to the shaft 11 and at 18 to provide a bearing for the belt 8. The front plate 15 is open at the center for the introduction of a feed pipe 10 to feed ore into the open space between the front and the back plates.

45 The front and the back plates of the accelerator wheel are rigidly connected together by vanes 19 which support the front plate. Flat vanes may be used and set radially or at an angle to the radius, or curved vanes may be used with the inner portion bent forward in the direction of rotation of the wheel, as indicated in the drawing, in order that ore fed through the spout or feed pipe 10 into the space between the front and back plates of the accelerator wheel may be more readily 55 forced to its periphery. In front of the feed pipe

there is an extension which extends for some distance in the direction of rotation of the wheel, as shown at 20. This extension serves to prevent escape of material through the open front plate of the wheel and may, if desired, be extended all the way around the circumference with the exception of an opening for the feed pipe 10. The feed pipe should preferably be so arranged that the feed is directed somewhat to the forward side of the point at which the belt coming from the rear pulley first makes contact with the accelerator wheel. When this is done the outer surface of the wheel is sealed against the escape of material before it reaches the point to which the feed is directed, and no material is fed between the belt and the wheel where its presence would result in wear of the belt or of the wheel, or of both. While this arrangement of the feed pipe is preferred for the reasons given, it is not indispensable that it be so arranged. Even when the feed pipe is so located as to discharge a moderate distance behind the point at which the belt coming from the rear pulley makes contact with the accelerator wheel, the vanes have a tendency to direct the feed forward before it reaches the outward periphery of the wheel and to prevent any substantial difficulties due to feed being trapped between the belt and the wheel.

5 A guard 21 may be mounted to cover most of that portion of the accelerator wheel which is not in contact with the belt 8. A narrow opening 22 is left uncovered for the egress of material fed into the accelerator wheel. While a guard or hood is not indispensable since even in its absence the greater part of the material fed into the wheel lies smoothly on the belt 8 and is removed by it, the guard does prevent a small amount of material from being thrown off in different directions and is, therefore, a desirable addition. Furthermore, with high belt speeds the accelerator wheel is rotated rapidly and tends to act as a fan drawing air in through the central opening in the front plate 15 and exhausting it at the periphery where it may carry with it dust from the ore fed into the machine. Fan action by the accelerator wheel is further undesirable in that it sets up air currents which interfere to some extent with the uniform motion of the stream of particles which is thrown from the moving belt. The guard substantially eliminates any fan action.

50 While the outside guard or hood 21 is probably the most effective means for the elimination of fan action by the accelerator wheel, and also serves the additional purpose of confining any material which may be thrown off by the upper

portion of the wheel and returning it to be fed onto the belt, the fan action may also be substantially eliminated by carrying the extension 20 of the feed pipe all around the circumference with the exception of an opening for the entrance of the feed pipe. This substantially closes the inner portion of the accelerator wheel and prevents the vanes from drawing air from the center and forcing it out. As an alternative to 10 this construction, the front plate of the accelerator wheel may be entirely closed except for an opening in which the feed pipe is arranged so as to make a tight fit, or the feed pipe may be passed through a stationary plate mounted close 15 to the front of the revolving accelerator wheel and arranged so as to seal the opening in the front plate.

It is preferable that the belt 8 make contact 20 with the accelerator wheel over a substantial arc instead of having a practically straight belt with which the accelerator wheel is in contact for only a short distance. When the belt is in contact 25 with the wheel for a considerable arc, it is clear from the drawing that the belt running onto the accelerator wheel from the rear pulley 7 will seal the outside of the space between the front and back plates of the wheel, and will form, 30 with the vanes 19, small pockets which are closed except on top. The pockets remain closed on the bottom until the belt leaves the accelerator 35 wheel. The ore fed into these pockets from above by the feed pipe 10 is brought up to the belt speed by the action of the vanes 19, and leaving the pockets at the belt speed when the belt departs from the accelerator wheel, is carried along by the belt without further acceleration.

In such a device it is also important that there be only a relatively short length of belt 40 between the accelerator wheel and the forward pulley 6, or if there be a long length of belt, that it be suitably supported or guided so as to cause it to run true and straight. With a long run of unsupported belt between the accelerator wheel and the forward pulley it is found that 45 vibrations of the belt are likely to occur and that these cause the stream of particles to be projected at varying angles. This results in undesirable irregularity in the operation of the machine.

50 In the operation of this machine for the separation or concentration of ores, the pulley 6 is rotated in the direction indicated by suitable means and the ore to be treated is fed into the upper end of the feed pipe 10. Passing through 55 the feed pipe the ore passes between the vanes 19 in the accelerator wheel and reaches the belt 8. Since the ore is brought up to belt speed by the vanes 19 while passing through the accelerator wheel it lies smoothly on the belt and moves 60 along with it until it is projected through the air as indicated at 23.

The ore which is treated with this apparatus 65 may be all of one size or may be a mixture of different sizes. In case the ore has been screened before feeding to the machine so that it consists of a closely sized material, the particles of different substances travel a different distance through the air depending upon their density and can be collected in separate piles. Each particle 70 as it travels through the air is retarded by the resistance of the air to its motion and for particles of equal size those of low density travel a shorter distance from the machine before falling to the ground than those of a high density. 75 Thus particles of valuable minerals such as

magnetite or gold or other heavy metallic ores or metals are separated from the lighter and less valuable materials such as sand and clay with which they are mixed when mined.

It is not necessary, however, that the material 5 be closely sized before feeding to the machine, and there are in some cases important advantages in postponing any sizing process until after the ore has been treated with the apparatus of this invention. The ore is simply 10 dried, crushed and disintegrated sufficiently to separate the particles of the heavier and more valuable minerals from lighter materials to which they may have been attached when taken from the ground. The entire mass is then fed into the 15 machine and projected through the air. In this case the feed will contain particles of a wide 20 variety of sizes, both of the mineral which it is desired to separate and of the material from which it is desired to separate it. In the treatment of sand containing gold it can be assumed 25 that the only materials which need consideration are gold and sand. When the ore is projected through the air the small particles of sand travel only a short distance before falling to the ground, while the progressively larger particles of sand fall progressively farther from the machine. A similar situation holds for the gold 30 particles, the larger ones falling farther from the machine than the smaller ones. If the 35 smallest gold particle is sufficiently large and the largest sand particle is sufficiently small, a substantially complete separation may be effected simply by passing the material through the machine, the smallest gold particle falling 40 farther from the machine than the largest sand particle. In general it will be found, however, that this favorable condition is not obtained and that both sand and gold particles will be found together in some of the material collected after 45 it has been thrown from the machine. In that portion of the material which falls at a specified distance from the machine, however, the gold particles will be smaller than the sand particles with which they are associated and can be separated from them by screening, or by some other method for the separation of particles of unequal size.

Furthermore, it has been found in the treatment 50 of certain ores containing gold that the material which falls anywhere within a certain distance from the machine consists almost entirely of sand and contains substantially no gold. This material can therefore be discarded and requires no further treatment for the separation 55 of gold. With this ore and a belt speed of about two thousand feet a minute, it has been found that the material which falls closest to the machine and contains so little gold that it can be discarded, amounts to some forty per cent of the 60 entire weight of the material treated. At higher belt speeds it appears that an even larger proportion of the entire mass contains substantially no gold and can be discarded without further treatment.

65 While equally favorable conditions may possibly not be found to exist in the treatment of other ores, there should, in all cases, be a certain amount of material which contains substantially no gold after being projected through 70 the air with this machine. Such material need not be subsequently treated, and it will, therefore, in general be found more advantageous to first pass the crushed and disintegrated but unsized ore through this machine, and then sepa- 75

5   ratey treat the fractions which fall at different distances from the machine to separate the gold particles from the larger sand particles with which they fall, than to first size the entire mass of ore and to then separately pass the various sized fractions through the machine in order to obtain a substantially complete separation of the gold from the sand particles. In the second case, the entire body of ore is subjected to a sizing 10 operation and is also passed through the apparatus of this invention; in the first case the entire body of unsized ore is passed through the machine, but only a portion is subjected to a sizing operation.

15   In sizing the different fractions that are collected at different distances from the machine when the unsized ore is passed through the screen, the fraction which falls just beyond the fraction which contains substantially no gold is 20 the one which contains the smallest particles of gold. This fraction should, therefore, be screened with a small mesh sieve. The small particles of gold fall through the sieve openings and form the concentrate from this fraction of material. The 25 larger sand particles are caught on the sieve and discarded. The fractions which fall progressively farther away from the machine contain progressively larger gold particles and are treated with sieves or screens of progressively 30 increasing screen openings.

The number of fractions of material which are separately screened will depend upon the results which it is desired to obtain. Since the material thrown from the machine is distributed 35 over the entire distance from the machine up to the greatest distance reached by any particle; any desired number of fractions can be collected. When a large number of fractions are taken, each fraction, or at least certain fractions, will 40 contain material which has been collected over a narrow range of distance from the machine. With a small number of fractions, on the contrary, there must be some fractions in which the material has been collected over a considerable

range of distance from the machine. The separate collection and screening of a large number of fractions, using screens with different size screen openings, is conducive to both a high degree of concentration and a high degree of recovery of the valuable constituent in the ore. The separate collection and screening of a smaller number of fractions is likely to lead to a lower degree of concentration if a high recovery is maintained, or to a lower recovery if a high 10 degree of concentration is maintained.

5   While this apparatus has been specifically described in connection with its use for the concentration of ores it is to be understood that it may also be employed for the concentration of 15 other substances, and the separation of a material of one density from a material of different density which is mixed with it.

10   We claim:

1. In an apparatus for the concentration of 20 ores, the combination of a belt, an accelerator wheel in contact therewith and having radially extending openings through its periphery, said belt being adapted to close the openings in the rim of said wheel over the area in which it contacts with the wheel, and a stationary feed pipe to feed ore radially outwardly into the openings in the rim of the accelerator wheel, said feed pipe being provided with an extension forward in the direction of rotation of the wheel to close 25 the inside of the openings in the rim of the accelerator wheel for a substantial distance.

2. In an apparatus of the class described, the combination of a belt, an accelerator wheel in contact therewith and having radially extending 30 openings through its periphery, and a stationary feed pipe to feed material radially outwardly into the openings in the rim of the accelerator wheel, said feed pipe being provided with an extension forward in the direction of rotation of the wheel 35 to close the inside of the openings in the rim of the accelerator wheel for a substantial distance.

40   SVEN MALKE.
ERIC A. KJELLGREN.
